UNITED STATES PATENT OFFICE.

EMIL R. DRAVER, OF RICHMOND, INDIANA.

MEANS FOR IMPARTING GYRATORY MOTION TO SIEVE-BOXES AND OTHER BODIES.

No. 830,309.

Specification of Letters Patent.

Patented Sept. 4, 1906.

Application filed June 22, 1906. Serial No. 322,847.

To all whom it may concern:

Be it known that I, EMIL R. DRAVER, a citizen of the United States, residing at Richmond, in the county of Wayne and State of Indiana, have invented certain new and useful Improvements in Means for Imparting Gyratory Motion to Sieve-Boxes and other Bodies; and I do hereby declare the following to be a full, clear, and exact description of the invention, such as will enable others skilled in the art to which it appertains to make and use the same.

My present invention has for its especial object to provide an improved mechanism for imparting gyratory motion to sieve-boxes of gyratory sifters, such as are commonly used for bolting or grading mill products.

The invention relates more particularly to the improvement of that type of motion-producing mechanism wherein a vertical driving-shaft is disposed centrally with respect to the sieve-box and is connected to the sieve-box by eccentrics, the said shaft being provided with eccentric or unbalanced weights, with the parts so arranged that the force of the weights will offset approximately the inertia of the sieve-box, whereby the box will be driven with a gyratory movement equal or approximately equal to the throw of the eccentrics, while the shaft itself will remain stationary or substantially stationary during the ordinary operation of the machine.

To the above ends the invention consists of the novel devices and combinations of devices hereinafter defined in the claims.

In the accompanying drawings, which illustrate the invention, like characters indicate like parts throughout the several views.

Referring to the drawings, Figure 1 is a vertical section taken on the line x' x' of Fig. 2, showing my invention applied to a sieve-box or gyratory sifter, some parts being broken away and some parts being shown in full; and Fig. 2 is a horizontal section taken through the machine on the line x^2 x^2 of Fig. 1.

The numeral 1 indicates the floor, and the numeral 2 the overhead support or ceiling, of a structure in which the machine is installed.

The numeral 3 indicates the sieve-box or gyratory sifter, the same, as shown, being suspended from the ceiling 2 by means of flexible rods 4. The sieve-box 3 is of the two-compartment type and is formed with a centrally-located open space 5, that runs from top to bottom thereof.

Rigidly secured to the sieve-box in the open space concentric to the vertical axis of the sieve-box and located one at the top and one at the bottom of said sieve-box is a pair of eccentric-seats or bearing-sleeves 6. A tubular shaft 7 extends vertically through the seats 6 and is provided with eccentrics 8, that work one in each of the said eccentric-seats 6. The said tubular shaft 7 is also provided with unbalanced weights 9, that extend laterally or eccentrically in a direction opposite to the offset of the eccentrics 8. These unbalanced weights 9 are located, preferably, as shown, one above and the other below the sieve-box.

The weight of the tubular shaft 7 is not sustained by the sieve-box, but, on the contrary, is taken by a flexible rod 10, which is passed loosely through said tubular shaft, is securely attached to the ceiling or overhead support 2 at its upper end, and at its lower end is provided with a ball-supporting cap 11, between which and the lower end of said tubular shaft 7 bearing-balls 12 are interposed. As shown, the upper end of the suspending-rod 10 is attached to a ceiling-bracket 13 by means of a pair of nuts 14.

To the lower end of the tubular shaft 7 a sleeve-like cup or cap 15 is secured, as shown, by means of a set-screw 16. This cap 15 serves as an oil-cup to hold oil, in which the bearing-balls 12 may run, and acts as an extension of the lower end of the tubular shaft 7 and co-operates with a relatively fixed annular thrust-limiting flange 17 to limit the extreme gyration of the said tubular shaft 7. As shown, the depending end of the cap 15 is reduced to form a trunnion 18, that works within the annular flange 17, and the said flange 17 is shown as cast integral with a rigidly-secured floor-plate 19.

Rotary motion is imparted to the tubular shaft 7 by a belt 20, that runs over a pulley 21 of a power-shaft 22, over a pair of idle guide-pulleys 23, secured to brackets 24 on the sieve-box, and over an eccentric-pulley 25 on the lower portion of said tubular shaft 7. The driving-shaft 22 is mounted in fixed bearings. (Not shown.) The eccentric-pulley 25 of the tubular shaft 7 is offset from the shaft 7 in the same direction as the offset of the eccentric 8, and it is offset with such amount of eccentricity that it will compensate for the lateral movement of the sieve-box with respect to the shaft 7, which is imparted thereto by said eccentrics 8. Other-

wise stated, the said eccentric-pulley 25 is so related to the eccentrics 8 that a constant tension of the belt 12 will be maintained when the said shaft 7 is rotated on its own axis and the sieve-box is gyrated about the same.

In starting the machine and before the proper or regular gyratory motion to the sieve-box has been acquired the shaft 7 will

- 10 take more or less of the gyratory motion, depending on the weight of the loaded box and upon the suddenness which the speed of rotation is imparted to said shaft. The annular flange 17 of the floor-plate 19 and the
- 15 depending end 18 of the cap 15 coöperate to limit the extreme movement which may possibly be imparted to the shaft 7 when the machine is thus started into action. After motion has been imparted to the shaft 7 for
- 20 a short time the sieve-box will acquire a regular gyratory motion which is approximately equal to the throw of the eccentrics 8, and the shaft 7 will settle down to approximately true rotary motion and will be given little or
- 25 no gyratory motion.

The driving mechanism above described, while simple and of small cost, is highly efficient for the purposes had in view.

The improved means above described for 30 imparting gyratory motion may of course be used generally wherever it is desired to impart gyratory motion to a movable body which is so suspended or supported that it is capable of such gyratory motion.

35 What I claim is—

1. The combination with a body, of means for gyrating the same comprising a shaft having eccentric connections therewith and having a driving-pulley eccentrically mounted thereon, and a power-driven belt running over said eccentric-pulley, with said eccentric-pulley arranged to compensate for gyratory movements of said body with respect to said shaft, whereby an approximately constant belt tension is maintained, substantially as described.

2. The combination with a freely-suspended body, of means for gyrating the same comprising a vertical shaft having eccentric connections with said body, and provided with unbalanced weights and having a driving-pulley eccentrically mounted thereon, idle guide-pulleys carried by said body, a driving-pulley supported independently of said body, and a driving-belt running over said driving-pulley, over said idle pulleys, and over said eccentric-pulley, the said eccentric-pulley being arranged to compensate for gyratory movements of said body, with respect to said shaft, whereby an approximately constant belt tension is maintained, substantially as described.

3. The combination with a freely-suspended body, of means for imparting gyratory motion thereto, comprising a vertically-dis-

posed, power-driven tubular shaft having eccentric connections to said body, and provided with an unbalanced weight, of a suspending-rod suitably supported at its upper end, extended through said tubular shaft, 70 and provided at its lower end with a bearing device engaging with the lower end of said tubular shaft and supporting said shaft, substantially as described.

4. The combination with a freely-suspended body, of a power-driven, vertically-disposed tubular shaft having eccentric connections to said body, and provided with an unbalanced weight, of a suspending-rod suitably supported at its upper end, extended 80 through said tubular shaft and provided at its lower end with bearing devices engaging the lower end of said shaft and supporting the same, and an oil-cup secured to the lower end of said tubular shaft and inclosing the 85 said bearing devices, substantially as described.

5. The combination with a freely-suspended body, of a power-driven, vertically-disposed tubular shaft having eccentric connections to said body, and provided with an unbalanced weight, of a suspending-rod suitably supported at its upper end, extended 90 through said tubular shaft and provided at its lower end with bearing devices that engage the lower end of said tubular shaft and support the same, an annular thrust-limiting flange secured below said tubular shaft, and an oil-cup secured to the lower end of said tubular shaft and inclosing said bearing devices, said oil-cup having a depending portion that works within said annular thrust-flange, substantially as described.

6. The combination with a freely-suspended body, of a power-driven, vertically-disposed tubular shaft having eccentric connections to said body and provided with an unbalanced weight and having a driving-pulley eccentrically mounted thereon, idle guide-pulleys carried by said body, a driving-pulley supported independently of said body, a belt running over said driving-pulley, over said idle guide-pulleys, and over said eccentric-pulley, and a suspending-rod suitably supported at its upper end, extended through said tubular shaft and provided at its lower end with bearing devices engaging the lower end of said tubular shaft and supporting the same, substantially as described.

7. The combination with a freely-suspended body, of a power-driven, vertically-disposed tubular shaft having eccentric connections with said body, and provided with unbalanced weights and having a driving-pulley eccentrically mounted thereon, idle guide-pulleys carried by said body, a driving-pulley mounted independently of said body, a belt running over said driving-pulley, over said guide-pulleys and over said eccentric-pulley, a suspending-rod suitably supported 130

at its upper end, extended through said tubular shaft and provided at its lower end with ball-bearing devices directly engaging the lower end of said tubular shaft and supporting the same, an annular throw-limiting flange secured below said tubular shaft, and an oil-cup secured to the lower end of said tubular shaft and inclosing said ball-bearing devices, said oil-cup having a depending por-

tion that works within said throw-limiting flange, substantially as described.

In testimony whereof I affix my signature in presence of two witnesses.
